ATTORNEYS.

UNITED STATES PATENT OFFICE.

RICHARD A. GREEN, OF CHICAGO, ILLINOIS.

AUXILIARY AIR-INLET FOR GAS-ENGINES.

1,333,913.

Specification of Letters Patent. Patented Mar. 16, 1920.

Application filed April 22, 1918. Serial No. 230,058.

To all whom it may concern:

Be it known that I, RICHARD A. GREEN, a citizen of the United States, residing at 2049 Harrison street, in the city of Chicago, county of Cook, and State of Illinois, have invented a new and useful Improvement in Auxiliary Air-Inlets for Gas-Engines, of which the following is a specification.

My invention relates to auxiliary air inlets for that class of engines in which liquid gasoline or other hydrocarbon is drawn into the explosion chamber, after having been suitably warmed and mixed with air to form an explosive mixture, and is there exploded to produce power for the propulsion of automobiles or other machinery, my invention being primarily designed for use on automobiles where it is necessary to vary the quantity of hydrocarbon and air as the speed varies or the conditions of the road change, and is designed to automatically supply just the required amount of air to produce the highest efficiency of the engine.

The special object of my said invention, is to provide an automatically operated air inlet and valve which will automatically supply just the amount of air required to produce the most efficient explosive mixture to the engine under all changes of speed or load.

Another object, is to construct an air inlet and valve without the use of springs or other parts liable to become worn, or out of working order.

Further objects consist in making an air inlet and valve regulator which will be inexpensive in construction; artistic in appearance; convenient of installation; and adapted to the various classes of gas engines and the varying conditions under which they are required to be operated.

In the accompanying drawings, in which similar characters of reference refer to corresponding parts throughout the different views,

Figure 1 represents a side elevation of my improved device, shown in cross section.

Fig. 2 represents a valve and stem in one piece.

Fig. 3 represents a valve weighted at its lower extremity.

Fig. 4 represents a valve seat with several ports instead of one central port as shown in Fig. 1.

55 In the drawings, 1 represents a suitable conduit, substantially circular in cross sec-

tion, for connecting the air manifold with the intake of the engine. At 2 it is extended and formed into a suitable shape for convenient attachment to the exhaust manifold, while at 4 it is formed into suitable shape for attaching to the intake. The brace 3 is provided to more firmly attach it to the adjoining parts and to provide the rigidity necessary to its proper construction.

At 5 I have provided said conduit 1 with a suitable valve seat substantially the full size of the outlet end 4 thereof, and centrally of said valve seat 5 I have provided the port opening 6, which I have preferably shown as a single opening of size suitable for the particular engine with which it is to be used. As will be seen, I have constructed the face of the valve seat at an angle to the perpendicular, in order that the weight of the valve may hold it securely upon the valve seat without the necessity of springs or other undependable means being required to insure the closing of said valve opening.

I have preferably made the valve in three parts, as shown, consisting of the valve cover proper 7, having the stem 8 which fits loosely within an opening in the arm 10, and is held in position thereon against accidental misplacement by the nut 9. The arm 10 is pivotally mounted upon the bolt or pin 14 which passes through suitable openings in the conduit and is firmly supported in position therein. By mounting the valve cover 7 loosely upon the arm 10, I have provided it with a certain amount of lateral movement, to permit it to adjust itself to the surface of the valve seat perfectly, thereby closing said port completely, and avoiding the possibility of an opening under said cover by reason of faulty construction, or warping, or poor adjustments.

At 11, on the inner side of the elbow formed in the conduit, I have formed a rectangular offset and thereby provided an air passage around the valve seat 5, as shown, to supply the engine with a limited amount of air when it is running idle, or light, without operating the valve above described. As will be seen, I have made this passage substantially rectangular in cross section as this shape lends itself to the artistic appearance, and also provides a suitable opening in which to mount the upper end of the arm 10. This passage way may be made of any suitable size to admit a proper amount of air

to provide the engine with the air necessary to run idle, or on light load, the port 6 remaining closed excepting when the amount of air required exceeds the amount admitted 5 through passage way 11.

In operation, air, suitably heated by passing through the manifold in proximity to the exhaust is admitted through the conduit 1, and the air passage way 11, and the outlet 4 as shown by the arrows 12, into the engine whenever it is operated in the usual manner. The air passage way 11 is of sufficient size to admit sufficient air for the engine when it is started, and before the clutch 10 is thrown in, the valve port 6 remaining closed as shown to limit the quantity of air to that which can be drawn in through the passage way 11. Whenever the load is increased to a degree that additional air is 15 required, the suction from the engine through the conduit 1 draws in an amount of air greater than can pass through the passage way 11, and this suction overcomes the pressure of the valve 7 upon the valve 20 seat and raises it sufficiently to permit such added air as may be required. It will readily be seen that the more rapid the action of the engine, and the greater the suction, the higher the valve 7 will be lifted, and the 25 greater will be the quantity of air entering through the port 6. By this construction the quantity of air thus admitted is automatically regulated by the suction of the engine, being greater, or less as the suction 30 increases or decreases, thus providing air to automatically mix with whatever quantity of gasolene is taken into the engine.

In the construction of my auxiliary air inlet, as shown, I have preferably shown the 35 passage way 11 as of rectangular cross section. While this shape readily lends itself to conform to my construction, it will be apparent that this passage way may be of any other desired form or shape, so long as 40 it supplies the required amount of air past the valve seat 5 and permits air to pass through it from the end 2 to the end 4 thereof. I have also preferably shown the valve port 6 as a single centrally round opening, 45 as this seems to be efficient in operation. It will be apparent that the port opening centrally of the valve seat 5 may be of any other desired shape, or may consist of a number of smaller openings designated at 50 6', as shown in Fig. 4, providing they be within the covered area of the valve seat, and be properly covered when the valve is closed, and permit the passage of the air 55 through them when the valve is opened in operation.

I have preferably shown the valve as consisting of the three parts 7, 9 and 10, the part 7 being loosely mounted upon the arm 10 to permit lateral play as described. By 60 this construction I consider that the valve

cover more readily adapts itself to the surface of the valve seat, and there is less likelihood of its becoming displaced, or not covering said valve seat perfectly. It may be made in a single piece, as shown at Fig. 2, 70 and if considered too light to regulate the admission of air through the valve port 6, may be especially weighted, as shown at 15 in Fig. 3, wherever the valve does not appear to be sufficiently weighted for heavy 75 work, on large engines.

I have preferably shown the valve seat 5 at an angle to the perpendicular, as I thereby increase the pressure of the valve against the valve seat, and this construction permits the use of a lighter valve, making it quicker acting, and more responsive, especially in the lighter small engines. While I have shown this angle as about thirty degrees, this angle may be made greater, or 80 less, as required for the especial engine with which it is to be used, or may be constructed to be adjustable for different engines without departing from the spirit of my said invention. 85

It will be seen that I have preferably constructed my said manifold stove and air passage and valve without the use of a spring or other mechanical device for returning the valve to its seat, depending 90 upon the weight of said valve to return it to its seat after each successive intake of the engine. By this construction I eliminate the cost of such additional means for returning said valve to its seat, and all liability of 95 said valve to become inoperative by reason of the breakage, wear, or displacement of such parts as frequently occurs where those additional parts are employed. 100

In operation, the above form of manifold 105 stove and air passage has demonstrated that it is highly efficient, and as I have explained, is easily adjustable and adaptable to various sizes of engines, and for engines performing a wide variety of work. While I 110 have shown the preferable construction of my manifold stove, I do not wish to be limited to the exact details of construction and combinations herein shown, it being obvious that minor variations thereof, not involving 115 the exercise of invention, may be made, without departing from the spirit thereof.

Having thus described my said invention, what I claim and desire to secure by Letters Patent, is the following:—

1. An air regulating device for gasolene engines, comprising an air conduit, a valve seat in said conduit, an offset chamber in said conduit adjacent said valve seat and forming a supplemental air passage around 125 said seat, and a valve having pivotal mounting in said chamber and adapted to normally engage said seat to close the conduit.

2. An air regulating device for gasolene engines, comprising an air conduit, a valve 130

seat in said conduit, an offset chamber in said conduit adjacent said valve seat and forming a supplemental air passage around said seat for supplying a predetermined amount of air continuously to the engine, and a valve having pivotal mounting in said chamber and adapted to normally engage said seat to close the conduit.

3. An air regulating device for gasoline engines, comprising an air conduit, a valve seat in said conduit, a rectangular offset

chamber in said conduit adjacent said valve seat and forming a supplemental air passage around said seat, and a valve having pivotal mounting in said chamber.

15

In witness whereof I have hereunto subscribed my name this 12th day of April, 1918.

RICHARD A. GREEN.
